OF HOPEDALE, MASSACHUSETTS, A CORPORATION OF MAINE.

LOOSE-WARP TAKE-UP.

1,027,887.

Specification of Letters Patent.

Patented May 28, 1912.

Application filed May 11, 1911. Serial No. 626,461.

To all whom it may concern:

Be it known that I, HERBERT W. OWEN, of Dover, in the county of Strafford and State of New Hampshire, have invented a Loose-Warp Take-Up, (Case B,) of which the following is a specification.

It frequently occurs that more warp threads are wound on the warp beam of a loom than are required in weaving the intended fabric. This surplus of warp threads on the warp beam is often intentional in order that there shall certainly be enough warp threads available for the fabric. The result of such surplus of extra warp threads is that they are apt to get among the warp threads which are being woven into the fabric and consequently warp breakage occurs and defects in the fabric are caused. Heretofore the looking after of these loose warps has been a source of annoyance and has required frequent attention on the part of the weaver.

The purpose of the present invention is to provide an automatic take-up for these loose warp threads. It is important in connection with such a loose warp take-up that it should be equally efficient irrespective of the location of the loose warp threads on the warp beam and irrespective of the varying rates of the feed of the warp due to differing numbers of picks in a given length of the fabric. It is likewise important that the mechanism should be simple and should require minimum attention and no adjustment on account of varying numbers of picks. The loose warp take-up constituting the present invention carries out these objects.

It is illustrated in the accompanying drawings, wherein—

Figure 1, is a vertical longitudinal section of so much of a loom as is necessary for an understanding of the present invention, the loom being equipped with the new take-up. Fig. 2, is a rear view of the take-up.

A, is a portion of the framework of the loom; B, is the warp beam; C, C, are the harnesses, a simple harness motion being shown comprising only two vertically reciprocating harnesses; and D, D, are the lease rods. The illustrated warp threads α , α , are those which are utilized in the weaving and which enter the finished fabric. Extra surplus or loose warp threads are shown at b ,

three such loose warps being indicated in Fig. 2. These loose warps pass from the warp beam B, over the usual whip roll R, and thence upwardly and forwardly to the loose warp take-up. This take-up includes a drum E, upon which the loose warps b , are wound. This drum loosely rotates upon an axle F, which extends horizontally across the loom and parallel with the warp beam. The take-up drum E, can be slid lengthwise of the axle F, so that it may be adjusted crosswise of the warp to any desired position opposite the warp beam, so that the loose warp threads may pass from the warp beam to the take-up through the shortest possible path. Several of the take-up drums can be mounted on the same axle. The axle F, is parallel with the warp beam and it has spindles c , at its opposite ends which rest in open bearings d , in brackets G, secured to the loom frame A. Accordingly, the axle can be readily removed at any time from the loom and the drum E, can be then slipped endwise off from the axle for the purpose of removing therefrom the warp threads wound thereon when the drum is full. An empty drum can be at once placed on the axle and the axle replaced on the loom, so that no cessation in the operation of the loom is necessary when a full take-up drum is removed and an empty one put in its place. For rotating the take-up drum it is equipped with a grooved pulley H, fast thereon with which coöperates a flexible driver I. This driver at one end is connected with the rear harness C. It can be readily connected with the harness at any part of the length thereof, so that the driver can coöperate with the drum wherever the drum may be located on the axle F. This driver I, is a band or cord passing over the grooved pulley H, and at its free end a weight J is attached to it.

When the rear harness, to which the driver I, is attached, rises, the weight J, descends, thereby rotating the drum backwardly in a direction to unwind the loose warps. When the rear harness descends it draws upon the driver I, thereby causing the take-up drum to rotate forwardly and hence to wind up the loose warps. If the connection between the driver I, and the drum pulley H, were a tight and uniform one, the drum would simply be oscillated

back and forth to equal extents and there would be no winding up of the loose warps. The driving arrangement shown, however, affords a loose drive which is more effective 5 to advance the take-up drum than to reverse it.

When the rear harness starts on its ascent, it moves more quickly than does the weight J, dropping by gravity, with the result that 10 the driver I, is slackened during the first portion of the ascent of the rear harness, thereby freeing the pulley H, of the friction of the driver to a substantial extent; and the full frictional effect of the weighted 15 driver as it drops is not realized until the rear harness has ascended part way. The consequence is that the down stroke of the rear harness is more effective in rotating the take-up drum than its up-stroke and 20 hence the take-up drum rotates forwardly to a greater extent than it rotates rearwardly. Therefore the loose warps are wound upon the take-up drum. The loose drive of the take-up drum is further im- 25 portant because the driver can slip when the loose warps are drawn taut and hence there is no danger of breaking the loose warps even though there is but a single one being wound on the take-up. Another 30 merit of the loose drive is that it is equally efficient no matter how fast or how slowly the fabric is advanced as the weaving pro- gresses and, consequently, no adjustment of the loose thread take-up is required. This 35 loose drive constitutes a slipping friction drive which slips sufficiently to avoid breaking the warp threads while effectively wind- ing them up irrespective of their accumula- 40 tion on the drum and the varying feed of the cloth.

The surplus warp threads on the warp beam which are wound up by the rotary take-up are not governed by the weaving instrumentalities (namely, the harnesses, the 45 cloth take-up and their coöperating devices) nor do they enter the fabric woven by the loom; and, accordingly, the take-up for the surplus loose warp threads is an element separate from the warp beam and the cloth 50 take-up, and it is important that it should perform its office of taking care of the surplus warp threads during the normal pro- gress of the weaving, and hence it is power- impelled and automatic in its action.

I claim:—

1. A loom having, in combination, a warp-beam; an axle removably mounted on the loom above the warp and parallel with the warp-beam; a take-up drum for the surplus warp-threads on the warp-beam which 60 do not enter into the fabric woven on the loom, said drum being independent of the cloth take-up, and being slidingly and rotatively mounted on said axle; and means for rotating said take-up drum. 65

2. A loom having, in combination, a warp-beam; an axle mounted on the loom parallel with the warp-beam; a take-up drum for the surplus warp-threads on the warp-beam which do not enter into the 70 fabric woven on the loom, said drum being independent of the cloth take-up, and being slidingly and rotatively mounted on said axle; and means for rotating said take-up drum. 75

3. A loom having, in combination, a warp-beam; an axle removably mounted on the loom; a take-up drum for the surplus warp-threads on the warp-beam which do not enter into the fabric woven on the loom, 80 said drum being independent of the cloth take-up, and being slidingly and rotatively mounted on said axle; and means for rotating said take-up drum.

4. A loom having, in combination, a warp-beam; a take-up for the surplus warp-threads on the warp-beam which do not enter into the fabric woven on the loom, said take-up being independent of the cloth take-up, and being adjustable crosswise of the 90 warp; and means for automatically moving said take-up. 85

5. A loom having a warp-beam and weaving instrumentalities, in combination with a take-up for the surplus warp-threads on the warp-beam which do not enter into the fabric woven on the loom, said take-up being independent of the cloth take-up, and being adjustable crosswise of the warp; and 95 means for moving said take-up. 100

In witness whereof, I have hereunto signed my name in the presence of two sub- scribing witnesses.

HERBERT W. OWEN.
